(57) **CLAIM**

The ornamental design for a power distribution cabinet as shown and described.

DESCRIPTION

FIG. 1 is a top, front and right side perspective view of a power distribution cabinet showing our new design; FIG. 2 is a bottom, rear and left side perspective view thereof;

FIG. 3 is a front and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The broken lines in the drawings illustrate portions of the power distribution cabinet which form no part of the claimed design.

1 Claim, 9 Drawing Sheets
